PNEUMATIC WEFT CONTROL MEANS
Lambertus te Strake, Huize Geiria, Deurne, Netherlands
Filed Jan. 23, 1961, Ser. No. 34,031
5 Claims. (Cl. 139—127)

This invention relates to loom apparatus in general and in particular to a device for periodically drawing a loop in a thread by pulling the thread in through the open end of a hollow shaft having a suction opening closable by a valve at the closed end. This suction opening is connected to a suction device, so that with the suction valve open air enters the shaft at its open end and with the suction valve closed the loop of thread can be readily drawn out of the shaft, without a suction action being exerted on it. The shaft is an improvement on the shaft disclosed in U.S. Patent No. 3,024,814 issued March 13, 1962, to Lambertus te Strake, such patent showing the location and operation of the shaft in a weaving loom.

Suction of air into the hollow shaft on one side of the loom occurs between the periods in which at the same side of the loom a weft thread is blown into the shed. The frequency of operation of this suction action for one hollow shaft is thus forced to be about 200 periods per minute at a high working velocity of the loom.

Because of the high frequency of operation the interruption of the suction flow of the air into the hollow shaft has to occur as rapidly as possible, so that the thread can be blown immediately into the shed and hence pulled out of the shaft. This means that the suction valve must close very rapidly to disconnect the suction line.

Flow interruption and the resultant kinetic energy of the air column in the shaft by closure of the valve causes very troublesome pressure wave formations. Due to the velocity of the air within the shaft, the air will be a little compressed at the closed end of the shaft immediately after the closing of the suction valve. Since the air is compressed it will expand and air will flow back toward the open end of the shaft tending to take the bottom of the U of the U-shaped loop of thread with it and entangling the thread.

It is an object of this invention to provide improved loom apparatus. It is a specific object of this invention to provide a loop drawing shaft as described herein wherein a rapid closure of a suction valve is possible, thereby allowing operational speed of the loom to be increased, while the consumption of air in the nozzles for the weft thread need not be higher than is necessary for a direct propulsion of the thread.

The invention features a provision between the open end of a hollow shaft and the suction opening at the closed end an air valve for increasing the self-frequency of a pressure wave occurring in the shaft as a result of closure of the valve of the suction opening. Thus the air column cannot start resonating and if a resonance might arise, a strong attenuation or damping takes place as a result of the logarithmic decrease of the arising pressure wave.

It is preferred that the distance between the air valve and the closed end of the shaft where the suction opening is provided, be such that the period of the pressure wave as a result of the closure of the valve is about $\frac{1}{4}$ of the original period determined by the length of the shaft.

Other objects, features, and advantages will become apparent when the following description is taken in conjunction with the accompanying drawings, in which:

FIG. 1 is a plan view of a shaft for drawing a loop in a length of thread;

FIG. 2 is a longitudinal section of the shaft shown in FIG. 1 taken along the line II—II in FIG. 1; and

FIG. 3 is a cross section of the shaft of FIG. 2 taken along the line III—III in FIG. 2.

2

The shaft is disposed at the side of the loom, near the shed. A thread running along the open end 1 of the shaft is drawn in a loop into the shaft when the thread is not under tension, as a result of the suction provided through a suction opening or aperture at the other end of the shaft 2.

The suction opening 2 can be closed by means of a valve 3. The opening 2 is connected to a suction device via the conduit 4. The shaft has formed therein a flat hollow recess or longitudinally extending thread receiving slit 5 having a conduit or enlarged channel 6 along the edge or periphery of the recess 5, said slit being of a width to readily admit said loop while preventing said loop from twisting.

15 The shaft housing comprises a lower half 7 and an upper half 8, these halves joined by suitable means such as threaded screws. Preferably the upper half 8 of the housing is made of transparent material, so that the loop of the thread, when it is present in the shaft, is 20 visible. This is desirable when the loom is not in operation for the repair of a weaving fault, broken thread, etc.

25 As appears from FIG. 3, the cross-section of the shaft has the shape of a dumb-bell or bar-bell, having two 20 conduits or enlarged channels 6 at the edges of the narrow slit 5.

30 In the lower half 7 of the housing there is formed a second aperture 9, access therethrough being controlled by a valve 10. Via the valve-housing 11 and the ports 12 the second aperture 9 is in communication with the atmosphere when the valve 10 is open. The second aperture 9 communicates with the thread receiving slit 5 intermediate the opening of the slit from the shaft and the suction aperture 2.

35 During the suction of the loop in the thread into the recess 5 the valve 3 is in the open position and the thread enters the shaft through the opening 1 in the shape or form of a loop. The substantially parallel threads of the loop lie in the conduits or channels 6 because the suction 40 pull is stronger in the channels.

At the moment that the thread is to be pulled out of the shaft the valve 3 is closed and the suction action ceases.

At the same moment that the valve 3 is closed, the valve 10 is opened, so that the effective length of the 45 shaft in connection with or relative to the resonance of the air column is suddenly interrupted. The valve 10 may also be opened a short period before closure of the valve 3.

50 In order to transmit the influence of the valve 10 with the appertaining second aperture 9 in the direction of propulsion of the pressure wave into the shaft, the second aperture 9 merges into an elongated longitudinal depression 13 formed in the lower half 7 and communicating with recess 5 where the second aperture 9 opens 55 into the recess 5 formed inside the shaft.

By opening of the valve 10 as described hereinbefore a correct damping of the pressure wave occurring during closure of the valve 3 is obtained, avoiding undesirable 60 secondary phenomena, causing the thread to leave the position obtained when drawn into the shaft by suction and thus avoid entanglement thereof.

I claim:

1. A device for temporarily collecting a thread while preventing entanglement thereof comprising a shaft having formed therein a longitudinally extending thread receiving slit; said shaft also having formed therein a suction aperture adapted to be utilized to lower the pressure within said slit whereby a thread disposed adjacent said slit is drawn in a loop into said slit; said slit being of a width to readily admit said loop while preventing said loop from twisting; first means disposed to control air flow through said suction aperture; a second aperture

formed in said shaft communicating with said thread-receiving slit intermediate the opening of said slit from said shaft and said suction aperture; and second means controlling air flow through said second aperture.

2. A device for temporarily collecting a thread while preventing entanglement thereof comprising a shaft having formed therein a longitudinally extending thread receiving slit; said shaft also having formed therein a suction aperture adapted to be utilized to lower the pressure within said slit whereby a thread disposed adjacent said slit is drawn in a loop into said slit; said slit being of a width to readily admit said loop while preventing said loop from twisting; first means disposed to control air flow through said suction aperture; a second aperture formed in said shaft communicating with said thread-receiving slit intermediate the opening of said slit from said shaft and said suction aperture; and second means controlling air flow through said second aperture; said second means being operative to admit air flow through said second aperture in response to a cessation of flow through said suction aperture.

3. A device for temporarily collecting a thread while preventing entanglement thereof comprising a shaft having formed therein a longitudinally extending thread receiving slit; said shaft also having formed therein a suction aperture adapted to be utilized to lower the pressure within said slit whereby a thread disposed adjacent said slit is drawn in a loop into said slit; said slit being of a width to readily admit said loop while preventing said loop from twisting; means disposed to control air flow through said suction aperture; a second aperture formed in said shaft communicating with said thread-receiving slit intermediate the opening of said slit from said shaft and said suction aperture; and means controlling air flow through said second aperture; said second aperture merging with a longitudinal depression formed in said housing and communicating with said thread-receiving slit.

4. A device for temporarily collecting a thread while preventing entanglement thereof comprising a shaft having formed therein a longitudinally extending thread receiving slit; said shaft also having formed therein a suc-

tion aperture adapted to be utilized to lower the pressure within said slit whereby a thread disposed adjacent said slit is drawn in a loop into said slit; said slit being of a width to readily admit said loop while preventing said loop from twisting; means disposed to control air flow through said suction aperture; a second aperture formed in said shaft communicating with said thread-receiving slit intermediate the opening of said slit from said shaft and said suction aperture; and means controlling air flow through said second aperture; said second aperture being spaced from said suction aperture by approximately one-fourth of the distance between said suction aperture and the shaft opening of said thread-receiving slit.

5. A device for temporarily collecting a thread while preventing entanglement thereof comprising a shaft having formed therein a longitudinally extending thread receiving slit; said shaft also having formed therein a suction aperture adapted to be utilized to lower the pressure within said slit whereby a thread disposed adjacent said slit is drawn in a loop into said slit; said slit being of a width to readily admit said loop while preventing said loop from twisting; said shaft having enlarged channels formed around the periphery of and communicating with said thread-receiving slit whereby suction pull is stronger in the channels thereby maintaining said thread in a U-shaped loop; means disposed to control air flow through said suction aperture; a second aperture formed in said shaft communicating with said thread-receiving slit intermediate the opening of said slit from said shaft and said suction aperture; and means controlling air flow through said second aperture.
